UNITED STATES PATENT OFFICE

HERMAN E. SCHULSE, OF BAYONNE, NEW JERSEY, ASSIGNOR TO H. E. SCHULSE, INC.,
A CORPORATION OF NEW YORK

SHOE SHINING LAST

Application filed June 5, 1928. Serial No. 282,967.

The present invention is concerned with the provision of a shoe supporting fixture which may be used for making small repairs on shoes, applying laces, etc., but which is primarily intended as a last for supporting shoes while they are being shined. It is embodied in a light fixture adapted to be conveniently attached to any suitable support, such for instance as a wall, and will serve to firmly support a shoe and effectively reinforce and back the shoe toe and counter, while the shoe is being operated upon.

An object of the invention is to provide a device of the above type which consists of only a few light castings that may be readily assembled and conveniently set for universal use with shoes of any and all sizes.

Another object of the invention is to provide a device of the character noted above upon which a shoe may be readily and securely emplaced and from which it may be readily removed.

Another object of the invention is to provide a shoe shining device adapted to be mounted on a wall or other support and being so constructed that it may be readily disengaged from its support without the use of tools when it is desired to conserve space by removing the projecting arm from the wall.

To accomplish these results I utilize for the shoe supporting means a two-part skeleton last including an arm adapted to be secured at one end to a suitable support; a relatively stationary member at the free end of the arm adapted to enter the toe of the shoe and a lever (preferably pivoted in the arm) carrying at its lower end a last member for the counter. When the shoe is placed on the forward last, the lever (preferably gravitationally) automatically swings to substantially correct position for engaging the movable last section with the inside of the shoe counter. Thus little or no manipulation of the lever is required. With the shoe in place the lever may be readily slightly shifted to move it snugly against the counter and then locked against swinging movement.

Preferably the means for rigidly mounting the arm includes a wall bracket and the arm

at one end is shaped for ready firm emplacement in or removal from the bracket without the use of tools. Thus when not required for use the projecting arm may be readily removed from the bracket and considerable space is then conserved.

Other and more general objects of the invention are to provide a shoe shining last of simple practical construction which will be rugged, durable and efficient in use and which is well suited to the requirements of economical manufacture, and convenient installation and manipulation.

With the above noted and other objects in view, the invention consists of certain novel features of construction and combination and arrangements of parts which will be more fully hereinafter described and pointed out in the claims.

The invention may be more fully understood from the following description in connection with the accompanying drawings wherein:

Fig. 1 is a perspective view showing a device embodying the invention mounted in its wall bracket, and illustrating in dotted lines the position of a shoe thereon.

Fig. 2 is a longitudinal vertical sectional view through the device.

Fig. 3 is an enlarged vertical sectional detail on the line 3—3 of Fig. 2.

Fig. 4 is an enlarged transverse sectional detail on the line 4—4 of Fig. 2 and

Fig. 5 is a sectional view on the line 5—5 of Fig. 2.

The device consists essentially of an arm 10 preferably of generally arched form, one end of which is removably mounted in a wall bracket 11. The other end of the arm 10 is shaped to define a last section 12 designed to enter the toe of a shoe and with which an adaptor 13 may be conveniently engaged. Pivotaly mounted at the intermediate portion of the arm 10 is a lever 14, the upper end of which constitutes a handle 15 and the lower end of which is shaped at 16 to form a counter last section to fit within the heel portion of the shoe and normally held by gravity in the position of Fig. 2. This is substantially the position in which it will

normally engage a shoe counter. Thus when a shoe 17 is emplaced on the forward last 12 or over the adaptor 13 the last section 16 which has been previously moved forward by pushing the handle 15 rearwardly will act to move back against the shoe counter in which position the lever handle after being pulled forward may be locked against movement in any suitable manner as by tightening the binding thumb screw 18.

It may be noted that this return movement of the lever is accomplished for the most part by gravity as the handle is released and after the shoe has been emplaced on the last 12 or adaptor 13 the rear last section 16 swings to substantially correct position to fit an average sized shoe by its own weight, after which but a slight manual adjustment is necessary before turning the thumb screw.

Preferably the bracket 11, the arm 10, and the lever 14 comprise three separate castings of light metal.

The bracket 11 is a longitudinally tapering plate having a suitable number of counter-sunk openings 20 therein for the reception of attaching screws 21 and adapted to be screwed flat against the wall 19. Integral strengthening webs or flanges may project forward from the side edges of the plate, these flanges following such edges and thus converging towards the plate bottom.

Sets of undercut lugs 23, 24 are provided at the upper end and lower end of the webs 22. The beveled undercut inner faces of these two sets of lugs also converge towards the bottom of the plate 11 so that an attaching plate 25 integral with the arm 10 may be conveniently slid into the bracket 11 and wedged in place between the lugs. The bevelled edges 26 of the tapering plate 25 dovetail with the undercut lugs 23. Preferably as the plate 25 rides down into place between the pair of lugs 23, 24 it does not contact with the body of the plate 11 but rides on small bearing projections 27, 28 arranged immediately above the respective lugs 23, 24. By using these projections and machining them, the necessity for machining the entire face of the plate is avoided and the only machining necessary is to smooth down the projections 27, 28 and the engaging faces of the lugs 24 and the plate 25.

Arm 10 and plate 25 form parts of the same casting, their union being reinforced by substantial strengthening and stiffening webs 29. These webs projecting downwardly from the top of the arm 10 extend substantially through the entire length of the arched arm and are spaced to form a channel in the bottom of the arm.

Near its middle, the arm 10 widens out and defines a pair of spaced, approximately circular substantial plates 30. These plates are separated by a vertical slot 31 in the arm and serve to integrally connect the forward last

section 12 of the arm with the rear plate bearing section thereof. The inner faces of the bearing plates 31 provide bearing surfaces for the enlarged fulcrum portion 32 of the lever 14 which extends through slot 31 between bearing plates 30. A rivet 33 passed centrally through bearing plates 30 and through enlargement 32 serves as the fulcrum of the lever. The enlarged intermediate portion of the lever also provides a surface to be engaged by the inner end of the thumb screw 18 which works through one plate 30 and when turned serves to releasably secure the lever against pivotal movement.

The free end of the arm 10 extends sharply downwardly from bearing plates 30 then turns forwardly where it gradually widens out into the shoe toe fitting last 12. This end of the arm 12 is longitudinally bowed to give the proper transverse configuration and transversely curved to give the desired longitudinal configuration. The shape of the member 12 may be substantially conventional.

Preferably at a point well inward from its end the last section 12 is provided with a central slot 34 through which the offset tail piece 35 of the adaptor 13 may be passed.

This adaptor is of proper longitudinal curvature to conveniently rest on and embrace the last 12. The adaptor may be of any conventional or convenient configuration, although the last and adaptor are preferably so designed that practically any type of women's shoe may be mounted on the last and any type of men's shoe mounted on the adaptor. The swinging movement of the last section 16 is principally relied on to compensate for differences in the lengths of the various shoes to be worked upon.

Near its tip the adaptor is provided with a depending lug 36 to abut the tip of the last section 12 and limit sliding movement of the adaptor on the last. The tail piece 35 on the other hand lies within the channel of the last and holds the adaptor against rocking movement when the pressure of a shining cloth or brush is applied to the shoe.

The operation of the device is substantially as follows:

Bracket 11 may be conveniently screwed to any suitable support such as a wall or a shoe shining stand, and the arm 10 may be readily attached to the bracket by simply sliding the plate 25 down between the lugs 23. The adaptor is applied to the last 12 by simply inserting tail piece 35 through the slot 34 and permitting the adaptor to drop to its normal position in which it straddles and embraces the last.

To apply the shoe, lever handle 15 is pulled rearwardly throwing the member 16 forwardly. The shoe is slipped over the adaptor 13 and when the handle 15 is released the counter last section 16 will swing rearwardly

to substantially the proper position. With most shoes only slight manual movement of the lever 14 is necessary to swing the member 16 firmly against the counter of the shoe prior to tightening the thumb screw 18.

After the shoe has been shined a slight turn of the screw 18 releases the lever and permits the shoe to be readily withdrawn.

Due to the fact that the arm 10 may be readily connected to its supporting bracket by merely lifting it up out of the bracket, the device is well adapted for use in locations where permanent fixtures occupy an undesirably large amount of space. The present device may be set up in a moment and readily detached and moved out of the way when not in use.

When a shoe is in place on the last and being operated upon, the pressures and strains transmitted through the work to the arm 10 are almost entirely downward and forward pressures induced by the polishing rag or brush on the toe and counter of the shoe. Thus such pressures have no tendency to dislodge the arm from the wall bracket. The downward pressures in fact tend to more firmly jam the plate 25 into the bracket.

The means for limiting the range of swinging movement of the lever and consequently the range of adjustment of the last section 16 is the engagement of the lower section of the lever with the downwardly extending forward section 12 of arm 10 as the handle 15 is pulled rearward and the engagement of the intermediate portion of the lever with the forward wall of slot 31 as the handle is pulled forward.

It will thus be seen that there is herein described a device in which the several features of this invention are embodied and which device in its action attains the various objects of the invention and is well suited to meet the requirements of practical use.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. As a new article of manufacture a shoe shining last including a relatively fixed arm, the free end of which constitutes the toe engaging portion of the last, means movably connected to said arm constituting the counter engaging portion of the last, said toe last portion of the arm being of curved shape in cross section and having an opening therein adapted to anchor a curved adaptor seating on and embracing the said toe last portion.

2. As a new article of manufacture a shoe shining last including a relatively fixed arm the free end of which constitutes the toe engaging portion of the last, a lever pivotally connected on a fixed pivot to the arm, the free end of said lever being shaped to constitute the counter engaging portion of the last, said lever being normally gravitationally urged to a position where the two last members will approximately fit an average sized shoe.

3. As a new article of manufacture a shoe shining last including a relatively fixed arm, the free end of which constitutes the toe engaging portion of the last, a lever pivotally connected intermediate its ends to the arm, one end of said lever constituting the counter engaging portion of the last, said arm being vertically slotted at its intermediate portion, the lever being fulcrumed in said slot, and the lever and walls of said slot being enlarged to provide substantial cooperating bearing surfaces for the movement of the lever.

4. As a new article of manufacture a shoe shining last including a relatively fixed arm, the free end of which constitutes the toe engaging portion of the last, a lever pivotally connected to the arm, the free end of said lever constituting the counter engaging portion of the last, said arm being vertically slotted at its intermediate portion, the lever being fulcrumed in said slot, the lever and walls of said slot providing substantial cooperating bearing surfaces for the movement of the lever and a binding screw working through one wall of the slot and engaging said lever.

5. As a new article of manufacture a shoe shining last including a relatively fixed arm, the free end of which constitutes the toe engaging portion of the last, a lever pivotally connected intermediate its ends to the arm for free swinging movement throughout a substantial range, one end of said lever constituting the counter engaging portion of the last, said arm being vertically slotted at its intermediate portion and the lever being fulcrumed in said slot, the end wall of the slot limiting the movement of the lever in one direction and the arm adjacent the toe last section limiting the movement of the lever in the opposite direction.

6. As a new article of manufacture a shoe shining last including a relatively fixed arm, the free end of which constitutes the toe engaging portion of the last, a lever pivotally connected intermediate its ends to the arm, one end of said lever constituting the counter engaging portion of the last, said arm being vertically slotted at its intermediate portion, the lever being fulcrumed in said slot, said arm being of generally channeled formation throughout its length, the slot intersecting said channel and widening it and the arm being of increased width adjacent the region

of the slot to strengthen the pivotal connection.

7. As a new article of manufacture a shoe shining last including a relatively fixed arm, the free end of which constitutes the toe engaging portion of the last, a lever pivotally connected to the arm, one end of said lever constituting the counter engaging portion of the last, a wall bracket including guideways, said arm including a plate portion at one end sliding in said guideways, said guideways including pairs of spaced lugs and said wall bracket comprising a substantially flat casting formed with machined projections on which the plate portion rides.

8. As a new article of manufacture an adaptor for shoe shining lasts comprising a longitudinally bowed transversely curved member of tapering shape adapted to fit within the toe of a shoe and including at its rear edge an offset hook portion disposed substantially parallel with the main axis of said member, and adapted to engage in a slot in the last.

9. As a new article of manufacture an adaptor for shoe shining lasts comprising a longitudinally bowed transversely curved member of tapering shape adapted to fit within the toe of a shoe, including at its rear edge an offset hook portion disposed substantially parallel with the main axis of said member, and adapted to engage in a slot in the last and including near its tip a depending lug on its underface adapted to abut the tip of the last.

10. As a new article of manufacture, a shoe shining last including an arm, one end of which is suitably shaped to engage the inside of the toe portion of a shoe, an adaptor likewise shaped to engage the inside of the toe of a shoe and to be mounted upon said end of the arm of the last, said arm and said portion having means to retain the adaptor in place, both the adaptor and said end of the arm having a form corresponding to the inside of the toe portion of a shoe for substantially filling said toe portion when the shoe is put on said last.

Signed at New York, in the county of New York and State of New York, this 2nd day of June, A. D. 1928.

HERMAN E. SCHULSE.
